COMBINED HANDBAG, SHOPPING BAG, AND MEMORANDA HOLDER

Jeanne Kiernan, New York, N. Y.

Application June 10, 1948, Serial No. 146,882

Term of patent 3½ years

(Cl. D87—3)

To all whom it may concern:

Be it known that I, Jeanne Kiernan, a citizen of the United States of America, residing in New York city, county of Kings, and State of New York, have invented a new, original, and ornamental Design for a Combined Handbag, Shopping Bag, and Memoranda Holder, of which the following is a specification, reference being had to the accompanying drawing, forming part thereof, wherein,

Figure 1 is a front elevational view of a combined handbag, shopping bag, and memoranda holder, showing my new design in closed position.

Figure 4 is a perspective view, on a smaller scale, of the combined handbag, shopping bag, and memoranda holder, showing the handbag element open and with the snap-on handles removed and showing the shopping bag element in an open position.

I claim:

The ornamental design for a combined handbag, shopping bag, and memoranda holder, substantially as shown and described.

JEANNE KIERNAN.
